WILHELM RESCH, OF BINNINGEN, SWITZERLAND.

APPARATUS FOR DYEING, BLEACHING, OR TREATING WITH FLUIDS AND CENTRIFUGING TEXTILE AND OTHER MATERIALS.

1,095,028.

Specification of Letters Patent. Patented Apr. 28, 1914.

Application filed August 20, 1912. Serial No. 716,031.

To all whom it may concern:

Be it known that I, WILHELM RESCH, dyer, a citizen of the Swiss Republic, residing at Binningen, Switzerland, have invented certain new and useful improvements in or relating to apparatus for dyeing, bleaching, or treating with fluids and centrifuging textile and other materials; and I do hereby declare the following to be a full, clear, and exact description of the invention, such as will enable others skilled in the art to which it appertains to make and use the same.

This invention relates to apparatus for dyeing, bleaching or otherwise treating with fluids and centrifuging textile and other materials of the type in which a vacuum can be produced in the inner space of the casing during the centrifuging.

One construction of apparatus is illustrated by way of example in the accompanying drawing in which,

Figure 1 is a sectional elevation, and Fig. 2 a horizontal cross section.

The compartments or boxes *l* in which the material to be treated is closely packed, are introduced from above into the drum *a* through a charging opening formed in one side of the cover *d*. In order to reduce the amount of liquid employed, the clearance spaces in the drum between the boxes *l* are filled as far as possible by water-tight hollow bodies *k*. The drum *a* is mounted on a vertical spindle *c* supported in the casing *m* of

the machine and in the cover *d*. The dyeing, bleaching, washing or the like of material, such, for example, as spools, bobbins, or cops of thread or yarn is effected in the following manner:—After the boxes *l* have been packed full with the material to be treated by means of some separate pressure apparatus, they are introduced into the drum *a* and firmly pressed by means of screws *e* outward against the wall of the drum. The centrifugal drum *a* with its contents is raised, for instance by means of a liquid under pressure acting on the lower end *h* of the spindle, and in that way the upper edge of the drum is pressed against the packing *b* on the cover *d* of the casing, so that two closed chambers will be produced in the casing. To insure the drum being pressed firmly upward, separately adjustable pressure screws *i* are provided. The pressure screws *e* can be either operated

singly, or mechanically connected together, to enable them all to be simultaneously adjusted.

The lateral wall of the drum *a* within the packing chamber *f* as well as the circumferential walls of the boxes *l*, are perforated like a sieve. Special importance is attached to the provision of an absolutely tight joint by means of the frame *f*, between the outer space and the inner space, so that any dyeing, bleaching or washing liquid, air, gases or the like, introduced into the outer or into the inner chamber, can pass into the boxes *l* only through the perforated walls, and further through the material they contain or vice versa, before being able to pass into the other chamber. This arrangement insures the most thorough impregnation possible of the fibers of the material and at the same time results in the expulsion of air from the material as the air contained therein is forced out. Similarly air and gas of any kind may be forced through the material in either direction, for instance, for the purpose of oxidizing. The surplus liquid adhering to the threads or fibers can also be carried away to a great extent by means of the air passing through them. Even where there is a considerable excess of pressure, the liquids, gases or the like must always pass exclusively through the tightly packed material as the packing rings prevent it from passing outside the material to be dyed.

After the dyeing, bleaching or like process is finished, the pressure screws *i* are loosened, and the drum *a* lowered, whereupon the centrifuging of the material under treatment can be effected in a well known manner by means of a belt drive on the vertical spindle. If it is necessary to effect the centrifuging of the dyed material in a vacuum, as for instance in the case of sulfur dyes, this is effected by the dye and the gases or the like contained being pumped, by means of an efficient pump *g*, out of the closed casing. The reversibility of the circulation will be at once seen from the drawing.

The apparatus described, differs from those of the known type, since the inner space of the casing can be under a vacuum during the centrifuging.

What I claim is:—

1. Apparatus for dyeing, bleaching and the like, comprising a closed casing, a rotary

drum therein having perforate wall sections, means for raising the drum to engage the upper edge thereof with the casing to make a fluid tight joint, removable boxes in said drum having perforate end sections, and means for holding said boxes in the drum with the perforate ends thereof registering with the perforate wall sections of the drum.

2. Apparatus for dyeing, bleaching and
10 the like, comprising a closed casing, a rotary drum therein having perforate wall sections, means for raising the drum to engage the upper edge thereof with the casing to make a fluid tight joint, removable boxes in said drum having perforate end sections, means for holding said boxes in the drum with the perforate ends thereof registering with the perforate wall sections of the drum, and

means for circulating fluid through the boxes and casing in either direction.

3. Apparatus for dyeing, bleaching and
20 the like, comprising a closed casing, a rotary drum therein having perforate wall sections, removable boxes having perforate ends disposed adjacent the perforate wall sections in fluid tight engagement therewith, means for effecting a fluid tight joint between the upper part of the drum and the casing, and means for circulating fluid through the boxes and casing in either direction.

25 In testimony whereof I have affixed my signature in presence of two witnesses.

30 WILHELM RESCH.
